UNITED STATES PATENT OFFICE

MICHAEL A. S. LAVIGNE, OF WINSTED, CONNECTICUT, ASSIGNOR OF SEVENTEEN PER CENT TO AMIN M. KHOURY, OF BURLINGTON, VERMONT

OIL BURNER

Application filed April 11, 1928. Serial No. 269,206.

This invention relates to new and useful improvements in oil burners, its primary object being to provide an oil burner that will generate a combustible gas by vaporizing the crude oil fuel without any forced draught or other mechanical aid. This is accomplished by having an oil trough, in which the fuel is burned, in the base of the apparatus and a plurality of perforated partitions situated around the said oil trough and having a plurality of parallel passages extending around and between said partitions and outer casing, which form the draft passages and the combustion chamber.

Another object of the invention is to provide an oil burner of the character described that is inexpensive to manufacture in consideration of the advantages offered, efficient and durable in service, positive in action and a general improvement in the art.

Another important feature of the invention is that owing to the manner in which the partitions are held in place, they may be easily renewed when they become burned by the excessive heat. This also applies to the top baffles which are likewise subject to the heat.

With these and other objects in view as will appear as the description proceeds, the invention consists in the novel construction and arrangement of parts as hereinafter more specifically set forth, claimed and shown in the accompanying drawings forming a part of this present application and in which:

Fig. 1 is a perspective view showing complete installation of my invention in a typical domestic furnace.

Fig. 2 is a side elevation of the oil burner.

Fig. 3 is a plan view of the oil burner with top baffles partially removed.

Fig. 4 is a cross-section along line A—A of Fig. 3.

Fig. 5 is an enlarged view of ball and socket joint of the stand.

Referring more in detail to the drawings in which similar reference characters designate corresponding parts throughout the several views it will be seen that the invention comprises a base 10 in which is located a shallow oil trough 11 and a feed passage 12

into which is connected a feed pipe 13. Sup-

ported on this base in grooves or checks provided therefor are two perforated partitions, an inner one 14 and an outer one 15, the space between them forming the combustion chamber 16 and an outer casing 17. A number of baffles or covers are provided and are checked in a similar manner to the base to receive the perforated partitions 14 and 15 and the outer casing 17. The center baffle 18 is fitted to the inner partition 14 while the outer baffle 19 is fitted to the outer partition 15 and the outer casing 17, and forms a cover for the outer draft passage 20. The baffle 21 forms a cover for the central draft passage 22. Suitable spaces 23 are provided in the base 10 to permit the air to enter these draft passages 20 and 22. 24 is a flame baffle located immediately above the oil trough 11, its purpose being to assist in breaking up the flame. The outlet 25 is in the baffle or cover 21 at the upper end of the combustion chamber. A priming trough 26 is placed underneath the base 10 and is connected to a pipe 27 extending outwards to a filler 28 having a lid 29. Extending over the entire apparatus is a canopy 30 supported on a pipe 31. The pipe being in turn supported at the top by a lug 32 on the baffle 19 and near the bottom by a lug 33 on the base 10. The lower end of the said pipe 31 is connected to the pipe 27 and in this manner supports the priming trough 26. The stand 34 is connected to the base 10 by a ball and socket joint 35 having a tightening bolt 36 and a nut 37, as a means of permitting the oil burner to be perfectly levelled when set in the fire box of a furnace. A needle valve 38 and float 39 are used to supply a constant oil level in the oil trough 11, and are located in valve casing 40 outside the furnace. Said valve casing 40 is connected to the feed pipe 13 and the pipe 41 which conveys the oil from the fuel tank 42. This tank is of special design being fitted with a mirror 43 on the front and filler spout 44 of an oil gauge glass 45 on the side of same.

It will be seen from the foregoing paragraphs that in order to light the burner a supply of gasoline is first poured into the priming trough 26 through the filler 28 a

match is then applied to the gasoline in the 5
filler and the lid 29 closed down, which will
cause the flame to come out around the priming
trough 26 and heat the oil in the oil
trough 11. This combined with air which
will be drawn in through the air inlets 23
and into the draft passages 20 and 22 then
through the perforations in the partitions
14 and 15, will generate a combustible gas in
10 the combustion chamber which will become
ignited from the flames of the burning gaso-
line. When the gasoline in the priming
trough is consumed the burner will be suffi-
ciently heated to generate the gas from the
15 inflowing fuel oil without any supplementary
side. The object of the canopy 30 is to re-
flex the heat onto the burner. The unburned
gas and a quantity of heated air is carried
down the pipe 31 and released from the prim-
20 ing trough to re-enter the burner through
the air inlets 23. The pre-heated air will
more readily form the combustible gas than
the cold. Thus it will be seen that the greater
heat that is obtainable the greater will be
25 the consumption of the air and therefore a
greater economy in the fuel oil.

It is believed that the construction and ad-
vantages of the structure shown may be ap-
parent from the foregoing paragraphs taken
30 in connection with the accompanying draw-
ings without further detailed description.

While the preferred embodiment of the in-
vention has been disclosed it is understood
35 that minor changes in the details of construc-
tion combination and arrangement of co-
operating elements may be resorted to within
in the scope of what is claimed without de-
parting from the spirit of the invention.

What I claim is:—

40 1. An oil burner, comprising a base mem-
ber, a fuel trough supported by said base
member, spaced perforated partitions ex-
tending vertically from the walls of said
trough, forming a combustion chamber above
45 the trough, an outer wall disposed in spaced
relation to the outer partition and supported
by said base member, a cover for said parti-
tions and wall having openings therethrough
communicating with the combustion chamber,
50 a canopy disposed above said cover in spaced
relation thereto, a priming trough disposed
beneath the base member adjacent the fuel
trough, a filler pipe connected with said
priming trough, and a return pipe extending
55 down from said canopy having connection
with said filler pipe, said base member having
air openings communicating with the space
between the outer wall and outer partition.

2. An oil burner, comprising a base mem-
60 ber, a fuel trough supported by said base mem-
ber, spaced perforated partitions extending
upwardly from the walls of the trough form-
ing a combustion chamber, an outer wall
spaced from the outer partition supported by
65 the base member and forming an air chamber,

70 said base member having air vents communi-
cating with the air chamber, a cover for the
partitions and outer wall having openings
communicating with the combustion cham-
ber, a canopy disposed above the cover, a
75 priming trough disposed beneath the base
member adjacent the fuel trough and air
vents, a filler pipe connected with said prim-
ing trough, and a return pipe extending down
from said canopy having connection with
80 said filler pipe.

In testimony whereof I affix my signature.
MICHAEL A. S. LAVIGNE.
